Isaac F Baker's

Design or ornament for furniture

"Major Heyward"

Patented April 10, 1849

D No 215

Des. 215

C. Cornelius & Co: assignee of J. F. Parker, Philadelphia Pat.
Letters Patent No. 215 dated April 10th - 1849.
The schedule referred to in these letters patent and
marking part of the same.

To all whom it may concern Be it known, that I Isaac
St. John of the City of Philadelphia, State of
Pennsylvania have invented & produced a new design
or figure for uniform or manumis called Major Beaumont
and I do hereby declare the following to be a full clear
and exact description thereof, it being had to the
accompanying drawing which is made part of this spe-
cification.

My design represents a human figure in a military
costume with a belt crossing the breast, a sword at the
left side and a riding whip in the right hand; the

2

Dec. 215

left resting on a broken off trunk of a tree, and the back
is made up of branches & foliage. The hat is pointed
in front. The coat is furnished with buttons and fac-
ings of a kind suited to a military dress. & the legs are
covered in riding boots, coming nearly to the knees—
That is to claim a maximum width and height to secure by
other's patent is the above described design called
Major Heyward, as fully set forth in the drawing
belong to aman and the use thereof as a furniture
ornament in whatever manner the same may be applied
Witnessed
